UNITED STATES PATENT OFFICE

144,083

DESIGN FOR A POWER SHOVEL CAB

Hilbert E. Swanson, Milwaukee, Wis., assignor to
Unit Crane & Shovel Corp., West Allis, Wis., a
corporation of Delaware

Application February 9, 1945, Serial No. 117,847

Term of patent 14 years

(Cl. D14—3)

To all whom it may concern:

Be it known that I, Hilbert E. Swanson, a citizen of the United States, residing at Milwaukee, in the county of Milwaukee and State of Wisconsin, have invented a new, original, and ornamental Design for a Power Shovel Cab, of which the following is a specification, reference being had to the accompanying drawings, forming part thereof.

In the drawings,

Fig. 1 is a left-hand side elevational view of a power shovel cab, showing my new design;

Fig. 2 is a right-hand side elevational view;
Fig. 3 is a front elevational view;
Fig. 4 is a rear elevational view;
Fig. 5 is a top plan view, and
Fig. 6 is a perspective view of the cab, showing the front, top and one side thereof.

I claim:

The ornamental design for a power shovel cab, substantially as shown.

HILBERT E. SWANSON.
